(57) **CLAIM**

The ornamental design for a table for electronic device, as shown and described.

DESCRIPTION

FIG. 1 is a perspective view of a table for electronic device, showing our new design;

FIG. 2 is a front view thereof;

FIG. 3 is a rear view thereof;

FIG. 4 is a side view thereof;

FIG. 5 is another side view thereof;

FIG. 6 is a top plan view thereof;

FIG. 7 is a bottom plan view thereof; and,

FIG. 8 is a bottom perspective view thereof.

The broken lines are for environmental purpose only and form no part of the claimed design.
